James N. Burlin, New York, N.Y., and James F. Ritchey, Carmel, and Stanley E. Seretny, Indianapolis, Ind., assignors to Bell Telephone Laboratories, Incorporated, Murray Hill, Berkeley Heights, N.J., a corporation of New York

Continuation-in-part of design application Ser. No. 86,421, Aug. 3, 1965. This application Mar. 27, 1967, Ser. No. 6,396

Term of patent 14 years

(Cl. D26—14)

FIG. 1

FIG. 2

FIG. 1 is a perspective view of a telephone set showing my new design; and

FIG. 2 is a side view of the telephone set, the opposite side being substantially a mirror image thereof.

This application is a continuation-in-part of our application Ser. No. D86,421, filed Aug. 3, 1965 and now abandoned.

The dominant features of the new design reside in the portions shown in full lines.

We claim:

The ornamental design for a telephone set, substantially as shown and described.
